IMPACT MEASURING UNIT FOR KARATE TRAINING

Andrew S. Siroki, 428 S. 8th Ave.,
Highland Park, N.J. 08904

Filed Jan. 16, 1974, Ser. No. 433,810

Term of patent 14 years

Int. Cl. D10—04

U.S. Cl. D10—83

FIG. 1 is a top plan view of an impact measuring unit for karate training showing my new design;

FIG. 2 is a left side elevational view thereof;

FIG. 3 is a right side elevational view thereof;

FIG. 4 is a front side elevational view thereof; and

FIG. 5 is a rear side elevational view thereof.

I claim:

The ornamental design for an impact measuring unit for karate training substantially as shown.
